UNITED STATES PATENT OFFICE.

ERNEST W. TRIK, OF NEW YORK, N. Y., ASSIGNOR TO BEATTIE MFG. CO., OF LITTLE FALLS, NEW JERSEY, A CORPORATION OF NEW JERSEY.

DESIGN FOR CARPET OR RUG.

44,502.

Specification for Design.

Patented Aug. 12, 1913.

Application filed June 21, 1913. Serial No. 775,148. Term of patent 3½ years.

To all whom it may concern:

Be it known that I, ERNEST W. TRIK, a citizen of the United States, residing in the city of New York, borough of Brooklyn, in the county of Kings and State of New York, have invented a new, original, and ornamental Design for a Carpet or Rug, of which the following is a specification, reference being had to the accompanying drawing, forming part thereof.

The figure is a face view of approximately a quarter section of a carpet or rug showing my design.

I claim:

The ornamental design for a carpet or rug as shown.

ERNEST W. TRIK.
